BUCKLE FOR REVERSIBLE BELTS

Alvis C. Husketh, Kittrell, N. C.

Application May 9, 1935, Serial No. 20,693

6 Claims. (Cl. 24—191)

This invention relates to buckles particularly of that type used in connection with belts for personal wear, in which the so-called fixed end of the belt is secured or anchored to a pivoted bail or loop which is made in lever form to provide means for adjustably holding the other or free end of the belt in any desired position.

The objects of the invention are;

First, to provide a buckle of the type above indicated, which is adapted not only to have means to removably anchor or secure one end of the belt to the buckle but at the same time enable the wearer, without removal of said belt, or detaching said secured or anchored end of said belt, 10 to reverse said belt so that either of its two sides may be made to face outwardly or towards the back of front plate of the buckle.

Second, to provide a belt buckle which will permit the use of not only an ordinary type of belt but also a reversible duplex belt adapted for two-fold use, by the easy and quick rotation through one hundred and eighty degrees of the secured or anchored end of said duplex belt for the exposure or display of the selected design, or color on either of the two sides of said belt, and, 25 hence, effect by the use of a single belt and with no additional expense the equivalent of two separate and independent sport or dress belts of different color or design.

Third, to provide a buckle construction which will carry out all the operations, functions and advantages above pointed out without departing from the general shape or design of the adopted and popular types of buckles or including additional parts, and enable the same to be manufactured and sold at the same cost or less than similar buckles.

Other objects and advantages of the present invention will appear as the description of the accompanying drawing proceeds, and the manner of assembling and using the invention are disclosed.

However, it is to be understood that applicant's invention is not limited to the exact details herein shown or described, but it is intended to include as part of the same all such obvious changes and modifications of the cooperating parts as would occur to a person skilled in the art and as would fall within the scope of the structural characteristics and relative arrangement of elements to be hereinafter claimed.

In the drawing, in which similar reference characters indicate the same parts in the several figures,

Figure 1 is a rear elevational view of a belt

buckle, showing the secured and free ends of the belt connected thereto;

Figure 2 is an edge view thereof;

Figure 3 is an enlarged rear elevational view of the buckle, similar to Figure 1, with the free end of belt missing and the loop or bail with end of belt secured thereto rotated through an angle of ninety degrees;

Figure 4 is an enlarged rear elevational view, similar to Figure 1, with the loop or bail having been turned one hundred degrees, and showing the belt reversed so that its other side, with different color or design, faces away from the front of buckle;

Figure 5 is a section on line V—V of Figure 3; 15

Figure 6 is a section on line VI—VI of Figure 4;

Figure 7 is a section on line VII—VII of Figure 3;

Figure 8 is an enlarged perspective view of the pivoted belt clamping member with rotatable bail 20 or loop attached thereto removed from front plate of the buckle; and

Figure 9 is a perspective view of the rotatable bail or loop detached from and prior to being rotatably secured to the clamping member, as 25 shown in Figure 8.

In the practice of this invention, according to the form illustrated in the drawing, the body member of the buckle comprises a front plate 10 provided with rearwardly extending side flanges 30 11, 11, having inturned edges 12, 12, under which the free end 4 of the belt 3 is received to be gripped in the body of the buckle in the manner to be presently described.

The front plate 10 is also provided with rearwardly extending side ears 13, 13, on said flanges 11, 11, in which the clamping member 14 is hinged or mounted to swing on its pivots 15, 15, as shown in Figures 1 and 3. Said clamping member 14 is, preferably, built up, and is provided with a ridged 40 section 16, as illustrated in Figure 8, to frictionally engage and securely clamp the free end 4 of the belt 3 against the inner face of the front plate 10, as is common in this class of belts and needs no further disclosure.

Said hinged clamping member 14 is provided at its middle portion, and parallel with the ridged section 16, with a round hole or opening 17, into which is seated and rotatably secured an extension 19, formed on the bail or loop 18, having 50 a belt receiving slot 20, the end 21 of the extension 19 being upset or enlarged to prevent the withdrawal of said extension 19 from the opening 17 and insure a permanent rotatable connection between said clamping member 14 and bail 55

or loop 18, as clearly shown in Figures 5, 6 and 8.

From the foregoing described construction, it will be seen the bail or loop 18 not only moves with said clamping member 14, having a hinged connection with the front plate 10 of the buckle, but also has a rotary movement on said clamping member 14 on its transverse axis, thereby enabling said bail or loop 18 to have a combined hinged and pivotal movement or floating rotary motion with respect to said front plate 10, for purposes to be presently described.

By this construction, the bail 18, by means of its rotatable connection or attachment to a clamping means, or member 14, as disclosed, permits the belt securing means, or bail 18, to rotate about an axis which is angularly or normally related to the hinge axis of said clamping means, thereby enabling the easy and ready reversibility of a belt having one end secured to a belt securing means or said rotatable bail, and without detachment of the belt from the buckle.

The several parts of the buckle being constructed and disposed as described, the duplex belt B, preferably made a certain color or design on one side, as indicated in Figure 1, and adapted for dress or street wear, and a different color or design, as outlined in Figure 4, for sport activities on the other side, has its end 5 to be secured to the buckle laced through the belt receiving slot 20 of the rotatable bail or loop 18 and anchored or attached thereto by any suitable securing means 6, 6, as shown in Figures 1 and 2.

The free end 4 of said belt B is then passed between the rear face of front plate 10, flanges 11, 11 and the ridged section 16 of the hinged clamping member 14. The belt length being properly adjusted to fit the waist of the wearer, the clamping member 14 is rocked on its pivots 15, 15 by gripping the loop or bail 18, or pulling on the free end 5 of the belt B attached to said bail 18, to force said member 14 and its section 16 to assume the position shown in Figures 2 and 6, and thereby force the ridged section 16 of the clamping member 14 to securely grip the properly adjusted belt under the necessary tension and friction to prevent displacement.

If it is desired to reverse the belt B so that the design or color which faces on the inside, as shown in Figure 1, all that is necessary is to unclamp and remove the free end 4 of belt B from the front plate 10 and turn the rotatable bail or loop 18 with the belt end 5 anchored thereto through an angle of one hundred and eighty degrees into the position shown in Figure 4, and the side of the belt which was on the inner or side next to the wearer will be reversed and disposed on the outside and enable the wearer again to properly clamp the free end 4 of the belt B, as heretofore explained, without having been required to detach or disturb the anchored or secured relation of end 5 of belt B with the rotatable bail or loop 18.

From the foregoing disclosure of the construction and operation of the improved buckle, all the objects and advantages recited in the statement of invention have been fully, cheaply and expeditiously carried out, and while I have not particularly described the construction of the belt, it will be seen that the buckle is always worn with the same design or initial side outside and each of the two sides of the belt may be built up of different styles, colors, designs, strips or laminations of material cemented or stitched together and used in conjunction with the novel buckle herein disclosed without being required to de-

tach or remove the duplex belt adapted for two-fold use from the buckle.

It will also be seen the invention is not necessarily limited to the exact form of belt buckle herein illustrated, but any buckle having a body section provided with means for attaching or securing one end of said belt to said body section and permit said attached end to be rotated through an angle of one hundred and eighty degrees and the other or free end of said belt to 10 be detachably engaged by said buckle or body section would be included in the broad or generic embodiment of the present invention.

What I claim is:

1. A buckle for a reversible belt adapted for personal wear, comprising a body section provided with a front plate, clamping means hinged to and cooperating with said body section for releasably securing the free end of said belt between said body section and clamping means, and means for securing the other end of the belt to said buckle, said means being rotatably connected to said clamping means about an axis which is angularly related to the hinge axis of said clamping means so as to permit the reversibility of said belt with respect to said front plate.

2. A buckle for a reversible belt adapted for personal wear, comprising a body section provided with a front plate, clamping means hinged to and cooperating with said body section for 30 releasably securing the free end of said belt between said body section and clamping means, and means for securing the other end of the belt to said buckle, said means being rotatably connected to said clamping means about an axis which is 35 normally related to the hinge axis of said clamping means so as to permit the reversibility of said belt with respect to said front plate.

3. A buckle for a reversible belt adapted for personal wear, comprising a body section provided 40 with a front plate, clamping means hinged to and cooperating with said body section for releasably securing the free end of said belt between said body section and clamping means, and a bail for securing the other end of the belt to said 45 buckle, said bail moving with and being rotatably connected to said clamping means about an axis which is normally related to the hinge axis of said clamping means so as to permit the reversibility of said 50 belt with respect to said front plate.

4. A buckle for a reversible belt adapted for personal wear, comprising a body section provided with a front plate, a rectangular shaped clamping means hinged to and cooperating with 55 said body section for releasably securing the free end of said belt between said body section and clamping means, and means for securing the other end of the belt to said buckle, said means being rotatably connected to the mid-section of said 60 clamping means about an axis which is normally related to the hinge axis of said clamping means so as to permit the reversibility of said belt with respect to said front plate.

5. A buckle for a reversible belt adapted for personal wear, comprising a body section provided with a front plate, clamping means parallel to and hinged to and cooperating with said body section for releasably securing the free end of said belt between said body section and clamping means, and means for securing the other end of the belt to said buckle, said means being rotatably 70 connected substantially through an arc of one hundred eighty degrees to said clamping means 75

about an axis which is normally related to the hinge axis of said clamping means so as to permit the reversibility of said belt with respect to said front plate.

5 6. A buckle for a reversible belt adapted for personal wear, comprising a body section provided with a front plate, a rectangular flat clamping means hinged to and cooperating with said body section for releasably securing the free end of said

belt between said body section and clamping means, and a flat elongated bail for securing the other end of the belt to said buckle, said bail being rotatably connected at its mid-section to said clamping means about an axis which is normally related to the hinge axis of said clamping means so as to permit the reversibility of said belt with respect to said front plate.

ALVIS C. HUSKETH.
